(57) **CLAIM**

The ornamental design for an RFID inlay, as shown.

DESCRIPTION

FIG. 1 is an isometric view of an RFID inlay showing my new design;

FIG. 2 is an enlarged view of a section of FIG. 1; and,
FIG. 3 is a plan view of FIG. 1.

The broken lines in the figures depict environment only and
form no part of the claimed design.

1 Claim, 3 Drawing Sheets

FIG. 1

FIG. 2

FIG. 3
